QUATERNARY AMMONIUM DERIVATIVES OF
N-ALKYLCARBAMOYLETHYL COMPOUNDS
Norbert M. Bikales, Livingston, N.J., assignor to Ameri-
can Cyanamid Company, Stamford, Conn., a corpora-
tion of Maine

No Drawing. Filed Sept. 28, 1964, Ser. No. 399,913
2 Claims. (Cl. 260—295)

This invention relates to quaternary ammonium derivatives of N-alkylcarbamoylethyl compounds. This invention also relates to novel cationic surface active compounds useful for bactericidal, nematocidal, antistatic, emulsifying, foam modifying, and various other purposes for which cationic surface active agents have been useful.

An object of the present invention is to provide quaternary ammonium derivatives of N-alkylacrylamide.

A further object of this invention is to provide quaternary ammonium derivatives of N-alkylacrylamides which are useful cationic surface active agents.

Other objects include providing methods of inhibiting the growth of bacteria and nematodes.

These and other objects and advantages of the present invention will become apparent from the detailed description which follows.

In accordance with the present invention there is provided a quaternary ammonium compound of the formula:

wherein R is the residue of an olefin having from about 6 to 40 carbon atoms and A is an anion, for example, a halogen.

The compounds of the present invention are readily prepared by methods known in the art. For example, one may start with N-alkylacrylamide wherein the alkyl group is R, and react with a pyridinium salt.

The N-alkylacrylamide starting material may also be prepared by methods known in the art, for example, by means of the well known Ritter reaction of an olefin, acrylonitrile and strong sulfuric acid as set forth in U.S. Patent 2,573,673 to Ritter or Ritter et al., JACS 70, 4045048 (1948). Various improvements have been made on the Ritter reaction for the provision of higher yields of the N-alkylacrylamides. Among these are the disclosures of application Serial No. 282,553, filed May 23, 1963 (continuation-in-part of S.N. 111,464, filed May 22, 1961, now abandoned), and application Serial No. 282,599, filed May 23, 1963 (continuation-in-part of S.N. 111,465, filed May 22, 1961 now abandoned).

The olefin residue R of the above formula is alkyl and is derived from olefins having about 6 and up to 40 carbon atoms, preferably from about 10 to 20 carbon atoms. These olefins are preferably further characterized as being predominantly straight chain, i.e., having a minimum of about 75% of straight chain materials. Suitable olefins are available from the petroleum industry. As examples of such olefins, the following are illustrative: hexene-1, heptene-1, octene-1, decene-1, decene-2, decene-3, decene-4, decene-5, undecene-1, undecene-2, undecene-3, undecene-4, undecene-5, dodecene-1, dodecene-2, dodecene-3, dodecene-4, dodecene-5, dodecene-6, tridecene-1, tridecene-2, tridecene-3, tridecene-4, tridecene-5, tridecene-6, tetradecene-1, tetradecene-2, tetradecene-3, tetradecene-4, tetradecene-5, tetradecene-6, tetradecene-7, pentadecene-1, pentadecene-2, pentadecene-3, pentadecene-4, pentadecene-5, pentadecene-6, pentadecene-7, hexadecene-1, hexadecene-2, hexadecene-3, hexadecene-4, hexadecene-5, hexadecene-6, hexadecene-7, hexadecene-8, octadecene-1, octadecene-2, octadecene-3, octadecene-4, octadecene-5, octadecene-6, octadecene-7, octadecene-8, oc-

tadecene-9, telomers of propylene and butylene such as propylene tetramer, propylene hexamer, triisobutylene, tetraisobutylene and the like. The side chain isomers of any of the foregoing compounds are obviously included. In the preparation of N-alkylacrylamide, these and other olefins may be employed singly or in combination with one or more of each other.

The anion A may be any of the anions of pyridinium salts, both organic and inorganic. Included are salt forming radicals and materials such as the halogens, e.g., chlorine, bromine and iodine; sulfate, nitrate, phosphate and like radicals; and carboxylate radicals such as formate, acetate and anions of sulfonic acids and the like. Various of said anionic radicals can be introduced directly into the molecules; and, in the case of others, they can be made, for instance, by substitution for halogen in the cation-active surface active agents of the present invention by known techniques as, for instance, by metathesis procedures.

As mentioned above the quaternary ammonium compound of this invention may be prepared by reacting a pyridinium salt with an N-alkylacrylamide. This reaction primarily differs from similar reactions in the prior art by the presence of the alkyl group in N-alkylacrylamide. Thus, by substituting the requisite N-alkylacrylamide in the prior art processes, the instant compound may be prepared. A suitable reaction for this purpose is disclosed by R. Dowbenko, J. Org. Chem. 25, 1123-1127 (1960). The synthesis described therein shows the preparation of the pyridinium chloride salt of acrylamide. The essential difference between this product and that of the instant invention is the absence of the olefin residue on the nitrogen atom of acrylamide. As will be shown herein-after, the presence of the olefin residue accounts for the surface activity as well as antibacterial and nematocidal activity of the present compound.

As antibacterial and nematocidal agents, the compounds of this invention may be applied directly and alone to the material to be treated or the compounds may be incorporated in conventional carriers or diluents and contacted with the microorganism. The choice of carrier or diluent is determined by the use of the composition as is the concentration of the active ingredient. Thus by admixture with an inert material such as talc, bentonite, kieselguhr, diatomaceous earth, and the like there can be prepared compositions suitable for admixture with or application to materials on which nematodes and bacteria feed. Also solutions of the compounds in organic solvents such as kerosene can be applied as sprays or impregnating baths or if desired with the use of pressure to facilitate penetration of the solution for treatment of various surfaces. Suitable formulations for application of the compound to articles subject to microbiological attack are also prepared by mixing the compounds with an emulsifying agent in the presence of organic solvents and then diluting with water to form an aqueous emulsion containing the compound.

The degree of solubility of the compound in water and in organic solvents will be determined primarily by the carbon content and structure of R the olefin residue. Thus it will be apparent that compatibility as well as surface activity of the compound may be controlled by choice of olefins used to prepare the N-alkylacrylamide reactant. For example, products wherein the R group is in excess of about 12 carbon atoms will have lower water solubility and therefore will be useful in extracting metallic anions from aqueous solution into an organic solvent.

In order that the present invention may be more completely understood, the following examples are given in which all parts are parts by weight unless otherwise specified. These examples are set forth primarily for the purpose of illustration and any specific enumeration of

detail contained therein should not be interpreted as a limitation on the case except where indicated in the appended claims.

Example 1

N-1-methylundecylacrylamide, 6.0 parts, obtained from the reaction of dodecene-1 with acrylonitrile, was dissolved with 2.9 parts of pyridinium chloride in 30 parts by volume of methanol in a suitable reaction vessel. The mixture was refluxed for 4 hours at atmospheric pressure. Thereafter, the solvent was stripped from the reaction mixture to give 8.1 parts of a brown, thick translucent gum in 91% yield. Upon standing, crystals were formed. Most of the oil was then dissolved away by the use of chloroform and the mixture evaporated. The infrared spectrum indicated the product to be mainly 1-[2-[(1-methylundecyl)carbamoyl]ethyl]pyridinium chloride. The product was easily and completely water soluble and surface active as indicated by the foam produced in aqueous solution. The product was also soluble in organic solvents such as the lower alcohols and chloroform.

Example 2

The compound of Example 1 was tested for antibacterial activity in a standard test substantially as follows.

From a 1000 p.p.m. solution of the compound, a 1 ml. aliquot in 9 ml. deionized water was placed in each of three test tubes. The test tubes were then each inoculated with one drop of *Staphylococcus aureus*, *Aerobacter aerogenes* and *Xanthomonas resicatoria*, respectively. The test tubes were allowed to stand 24 hours at room temperature and then 1 ml. of a solution containing 10% peptone broth and 1% dextrose was added to each of the test tubes. The test tubes were then incubated at 37° C. for 24 hours and thereafter observed for evidence of bacterial growth. The clarity of the solutions in the test tubes indicated complete inhibition of growth of the *Aerobacter aerogenes* and *Xanthomonas resicatoria* species and substantial kill of the *Staphylococcus aureus* species. As contrasted with this activity, the compound lacking the olefin residue, namely, N-(2-carbamoylethyl)pyridinium chloride, showed substantially no activity in kill or in inhibiting the growth of these bacteria.

Example 3

The compound of Example 1 was also tested for nematocidal activity in a standard activity test substantially as follows.

To 4 ml. of 0.1% solution of the compound of Example 1 in a stoppered vial was added sufficient cultured vinegar eel worm nematode to obtain a 100 p.p.m. concentration. The vial was then tumbled to provide intimate contact of chemical and organism. After 20 hours rotation on the tumbler, the eel worms were examined and percent mortality recorded. The compound of Example 1 showed good activity.

Example 4

By essentially the same procedure as in Example 1 the following compounds are prepared:

- 5 1-[2-[(1-methylheptyl)carbamoyl]ethyl]pyridinium chloride
 1-[2-[(1-methylnonyl)carbamoyl]ethyl]pyridinium chloride
 1-[2-[(1,1-dimethylundecyl)carbamoyl]ethyl]pyridinium chloride
 10 1-[2-[(1-methyltetradecyl)carbamoyl]ethyl]pyridinium chloride
 1-[2-[(1-methylnonadecyl)carbamoyl]ethyl]pyridinium chloride

15

Example 5

The following procedure is employed to prepare quaternary ammonium salts of this invention wherein R is straight chain alkyl.

In a suitable reaction vessel acrylyl chloride is added to n-dodecylamine and a suitable HCl acceptor, e.g., pyridine, in equimolar proportions in methanol. The reaction mixture is maintained cold, about 10° C., and the reaction proceeds spontaneously. On completion of reaction, pyridinium chloride is filtered off and the reaction product distilled to obtain N-n-dodecylacrylamide. This intermediate is then reacted with a pyridinium salt, e.g., pyridinium bromide, substantially as in Example 1, to form 1-[2-(n-dodecylcarbamoyl)ethyl]pyridinium bromide.

30

Example 6

By essentially the same procedure as in Example 5, the following compounds are made:

- 35 1-[2-(n-hexylcarbamoyl)ethyl]pyridinium bromide
 1-[2-(n-decylcarbamoyl)ethyl]pyridinium bromide
 1-[2-(n-tetradecylcarbamoyl)ethyl]pyridinium bromide
 1-[2-(n-octadecylcarbamoyl)ethyl]pyridinium bromide
 1-[2-(n-eicosylcarbamoyl)ethyl]pyridinium bromide.

40 I claim:

1. A quaternary ammonium compound of the formula:

wherein R is the residue of an olefin having from about 6 to 40 carbon atoms and A is an anion.

2. 1-[2-[(1-methylundecyl)carbamoyl]ethyl]pyridinium chloride.
